UNITED STATES PATENT OFFICE

2,561,836

WATER FILLING APPARATUS

Oscar M. Anderson, New Britain, Conn., assignor
to Landers, Frary & Clark, New Britain, Conn.,
a corporation of Connecticut

Application November 16, 1946, Serial No. 716,297

8 Claims. (Cl. 137—21)

1

The present invention relates generally to dishwashing machines and the like, and more particularly to a semi-automatic device for introducing a measured quantity of water to an associated apparatus such as a dishwashing machine.

It is an object of the present invention to provide a device which can be used in cooperation with a conventional source of tap water for facilitating the introduction of a measured quantity of water into a dishwashing machine or the like. It is an aim of the invention to provide such a device which is of simple construction and arranged for mounting with the machine in a compact and efficient manner adjacent a conventional type of water tap, as for example, beneath or adjacent a kitchen sink, without interfering with the normal usage of the sink and water tap.

It is a further object of the invention to provide such a measuring and filling apparatus for dishwashing machines which is semi-automatic in operation and thus not susceptible to accidental or inadvertent misuse. It is particularly desired to provide a device which will function substantially semi-automatically in the sense that water cannot be introduced into the device from the water tap while a measured quantity of water is being transferred from the device to a dishwashing machine and conversely that the device cannot be drained, i. e. its contents transferred to the dishwashing machine, while the device is receiving water from the water tap.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a top view of the device mounted in a conventional casing or cabinet supporting a kitchen sink;

Fig. 2 is a fragmentary side view partially in cross section showing the device in filling position;

Fig. 3 is a fragmentary side view partially in cross section with the device in draining position; and

Fig. 4 is a fragmentary top view partially in cross section taken along the line 4—4 of Fig. 3.

Referring to the drawings, the device of the

2

present invention is shown mounted in a suitable cabinet or casing 10 which supports a conventional kitchen sink 11. Arranged with the sink is a standard faucet 12 of the type which is pivoted at one end and has associated therewith the usual hot and cold water valves 13 and 14 in the usual manner.

In the specific embodiment of the invention shown in the drawings, the device is arranged 10 for use with a dishwashing machine 15 disposed in the cabinet or casing 10 beneath the sink 11. The dishwashing machine 15, for the most part, is shown only diagrammatically as the details of the machine form no part of the present invention. For the purposes of the present disclosure, it has been deemed necessary only to show the exterior of the dishwashing machine 15 which comprises the housing 16 and a water pump 17 secured to the bottom thereof.

20 The device of the present invention is positioned, in the embodiment shown, adjacent a rear corner of the dishwashing machine housing 16 and a rear corner of the sink 11 and is adapted to receive water to a predetermined amount 15 from the faucet 12 and then transfer this water, when desired, to the dishwashing machine 15. A main element of the device is a measuring tank 18 which, in the embodiment shown, is generally elongated and cylindrical in form and extends vertically alongside the dishwashing machine housing 16. The size of the tank 18 is such that, when it is filled with water, it contains the desired amount of water for use at one time in the dishwashing machine 15. The measuring tank 18 is connected directly to the dishwashing machine 15 by means of a suitable conduit 19 which communicates with an opening 20 in the bottom end member 21 of the measuring tank 18.

40 The measuring tank 18 is adapted to be filled with water through a filler tube 22 which is pivotally connected at one end to the upper end of a tube 23 which extends upwardly from the top end member 24 of the measuring tank 18. In accordance with the invention, the filler tube 22 is so constructed and mounted that it cannot be moved into a position where it may be filled with tap water from the faucet 12 without contemporaneously preventing the flow of water from the tank 18 to the dishwashing machine 15 and, conversely, that the transfer of water from the measuring tank 18 to the dishwashing machine 15 cannot be made to take place when the filler tube 22 is in position for receiving tap water from the faucet 12. In the specific embodiment shown

in the drawing, this is accomplished as follows:

The upper end of the tube 23 extends through the top of the cabinet or casing 10 and received therein is a bushing 25 which extends for a short distance into the tube 23 and which has an annular rim or flange 26 overlying the top board of the cabinet or casing 10, said flange 26 forming an upper shoulder upon which rests a flange 27 formed on the filler tube 22. The filler tube 22 extends downwardly within the bushing 25 and is pivotally retained therein by the snap ring 28 engaging the lower end of the bushing 25 and a shoulder 29 formed in the filler tube 22.

The outward extension or the length of the filler tube 22 is so related to the length of the faucet 12 that the filler tube is fillable with tap water from the faucet 12 only when the filler tube is pivoted to the position shown in Figs. 1 and 2. When the filler tube 22 is pivoted to the position shown in Fig. 3 and also shown in dotted lines in Fig. 1, it is entirely impossible for water to be introduced therein from the faucet 12. Means is provided to limit the pivoting of the filler tube 22 to the extent of the two positions referred to. This means comprises a pin 30 fixed to the tube 23 and a slot 31 in the filler tube 22 for receiving the pin 30, this slot 31 extending for only 90°, thereby limiting the pivoting of the filler tube 22 to a quarter turn, as previously described.

The pivoting of the filler tube 22 between filling and non-filling positions is utilized to automatically control the draining of the contents of the measuring tank 18 into the dishwashing machine 15. This is accomplished by providing a closure member or stopper 32 for the opening 20 in the bottom end member 21 and providing means for positioning the stopper in accordance with the pivoted position of the filler tube 22. The means utilized in the specific embodiment shown in the drawings to accomplish this operation comprises a perforated cup member 33 which is rotatably housed in the tube 23 to receive the extension 34 of the filler tube 22, such extension being of lesser diameter so as to be freely received within the cup member 33.

Extending between the stopper 32 and the cup member 33 and extension 34 is a connecting rod 35 which is fixed at its lower end to the stopper 32 and which, at its upper end, extends upwardly through the cup member 33 and is then bent at right angles to form a right-angled extension 36 which is slidably received in a slot 37 in the extension 34 of the filler tube 22 and which is secured at its end to the cup member 33.

As a result of the above construction, pivoting of the filler tube 22 from filling to non-filling position causes the connecting rod 35 and thus the cup member 33 to be pivoted a similar amount, this because of the connection between the filler tube 22 and the connecting rod 35 provided by the extension 36 received in the slot 37. The cup member 33 has secured to its bottom a generally triangularly-shaped member or segment 38 having an arcuate flange 39 of gradually increasing thickness in a clockwise direction, when viewed from above, thus providing a camming surface adapted to engage a stud 40 fastened to the tube 23. As a result of the pivoting of the cup member 33, the camming surface on the flange 39 causes the cup member 33 to slide laterally upwardly in the tube 23 carrying with it the connecting rod 35 which thus withdraws the stopper 32 from the opening 20. When the filler tube 22 is returned to filling position by pivoting in the reverse di-

rection, the cup member 33 is permitted to slide laterally downwardly in the tube 23 thereby reinserting the stopper 32 in the opening 20. The stopper 32 is provided with a series of prongs or guiding members 41 which assist in the positioning or directing of the stopper 32 into proper seating position within the opening 20.

It thus will be seen that, in accordance with the invention, the filler tube 22 can only cooperate with the faucet 12 for filling purposes when the filler tube is pivoted outwardly over the sink 11 and, when the filler tube is in this position, the measuring tank 18 will be filled to the top and any continuation of the filling operation merely causes the water to harmlessly spill over the top of the filler tube 22 into the sink 11. The overflow of the filler tube 22, of course, indicates to the operator that the measuring tank 18 has been filled. When it is desired to transfer the contents of the measuring tank 18 to the dishwashing machine 15, it is necessary only to pivot the filler tube 22 to its non-filling position where it is out of the way and will not interfere with the normal use of the faucet 12 or sink 11. When the filler tube 22 is pivoted to this position, it is, of course, entirely impossible to introduce any more water into the measuring tank from the faucet 12.

It will be appreciated that the construction of the device described above is simple and compact and may readily be combined with conventional sink cabinets or casings and with dishwashing machines and the like associated therewith. The device is semi-automatic in operation thereby greatly facilitating the introduction of measured quantities of water into an associated apparatus and it is so constructed that accidental improper use has been substantially avoided.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A filling device for introducing a measured quantity of water from a faucet to an associated apparatus comprising a measuring tank, a fluid passageway between the tank and the associated apparatus, a filler tube communicating with the tank and adapted to be moved into and out of water receiving position with respect to the faucet, means for opening and closing said passageway, and an interlock between said means and the filler tube for preventing movement of the filler tube into water receiving position when the passageway is open.

2. A filling device for introducing a measured quantity of water from a faucet to an associated apparatus comprising a measuring tank, a fluid passageway between the tank and the associated apparatus, a filler tube communicating with the tank and adapted to be moved into and out of

water receiving position with respect to the faucet, a closure member adapted to be moved into opening and closing position with respect to said passageway, interconnecting means between said closure member and filler tube whereby the closure member may be positioned by said tube, said means including an interlock whereby the closure member is retained in said passageway closing position except when the filler tube is in non-filling position.

3. A filling device for introducing a measured quantity of water from a faucet to an associated apparatus comprising a measuring tank, a fluid passageway between the tank and the associated apparatus, pivotally mounted filler tube for the tank adapted to be pivoted into and out of water receiving position with respect to the faucet, and closure means for the fluid passageway responsive to the pivoted position of the filler tube.

4. A filling device for introducing a measured quantity of water from a faucet to an associated apparatus comprising a measuring tank, a fluid passageway between the tank and the associated apparatus, a filler tube pivotally mounted at one end on the tank and adapted to be pivoted between water receiving and non-receiving positions with respect to the faucet, a closure member adapted to open and close said fluid passageway, and means responsive to pivoting movement of the filler tube for moving said closure member to opening position when the filler tube is moved to said non-receiving position and for moving the member to closing position when the tube is moved to water receiving position.

5. A filling device for introducing a measured quantity of water to an associated apparatus comprising a measuring tank, a fluid passageway between the tank and the associated apparatus, a filler tube pivotally mounted at one end on the tank for introducing water into the tank, a closure member adapted to open and close said fluid passageway, and connecting means interconnecting said filler tube and closure member whereby the closure member is actuated to open and close the fluid passageway in response to the pivoted position of the filler tube.

6. A filling device for introducing a measured quantity of water to an associated apparatus, comprising a measuring tank, a fluid passageway between the tank and the associated apparatus, a filler tube pivotally mounted at one end on the tank for introducing water into the tank, a stopper member adapted to be moved into and out of closing position with respect to said fluid passageway, and a mechanical interlock between the filler tube and stopper member whereby the stopper member is withdrawn and retained from closing position at a predetermined pivoted position of the filler tube.

7. A filling device for introducing a measured quantity of water to an associated apparatus from a faucet comprising a measuring tank, a fluid passageway between the tank and the associated apparatus, a stopper adapted to be moved into and out of closing position with respect to said passageway, a filler tube pivotally mounted at one end of the measuring tank and adapted to be pivoted into water receiving and non-receiving positions with respect to the faucet, a connecting rod connected at one end to the stopper and mounted at the other end for rotation by the filler tube, and cam means associated with said connecting rod for moving the rod longitudinally to withdraw the stopper from closing position when the filler tube is turned to said non-receiving position.

8. A filling device for introducing a measured quantity of water to an associated apparatus from a faucet comprising a measuring tank, a fluid passageway between the bottom of the tank and an associated apparatus, a conduit for admitting water to the top of the tank, a filler tube pivotally mounted at one end on the conduit and adapted to be pivoted between water receiving and non-receiving positions with respect to the faucet, a stopper adapted to be moved vertically into and out of seating position with respect to the fluid passageway, a connecting rod secured at one end to the stopper, a perforated cup member slidably disposed within the conduit, a right-angle extension on the connecting rod secured at the end to the cup member and received in a vertical slot in the filler tube whereby the rod and cup member are rotated when the filler tube is pivoted, a stud fixed to the conduit adjacent the cup member, and a cam surface on the cup member adapted to cooperate with the stud to raise the cup member and filler tube within the conduit and thus remove the stopper from its seat when the filler tube is pivoted to non-receiving position.
